WRIST DRIVEN ARM SUPPORT

Hans R. Lehneis, Merrick, N.Y., assignor to
New York University

Filed July 8, 1971, Ser. No. 160,997

Term of patent 14 years

Int. Cl. D24—03

U.S. Cl. D83—1 E

FIG. 1 is a perspective view looking from the top and left side of a wrist driven arm support embodying the present invention; and

FIG. 2 is a perspective view of the wrist driven arm support of FIG. 1 rotated 180° about its transverse axis.

I claim:

The ornamental design for a wrist driven arm support, substantially as shown.
